UNITED STATES PATENT OFFICE.

WILLIAM D. HAYNES, OF OMAHA, NEBRASKA.

OIL-BURNER.

1,277,581.

Specification of Letters Patent. Patented Sept. 3, 1918.

Application filed November 26, 1917. Serial No. 204,010.

To all whom it may concern:

Be it known that I, WILLIAM D. HAYNES, a citizen of the United States, residing at Omaha, in the county of Douglas and State 5 of Nebraska, have invented certain new and useful Improvements in Oil-Burners, of which the following is a specification.

My invention relates to improvements in oil burners and refers particularly to the 10 type or character of device used in a stove or range for employing oil as a fuel instead of coal.

The main object of my invention is the provision of an oil burner which will be 15 capable of instant application to the usual fire chamber of the stove and which will use oil under pressure as a fuel and which will be very economical, which will prevent the accumulation of carbon and secure the 20 highest degree of heat under all conditions.

Another object of my invention is the provision of an oil burner which can be produced at a small price, which will have a long life, and which will be thoroughly efficient and practical.

With these objects in view my invention consists of an oil burner of the type and for the purposes stated embodying novel features of construction and combination of 30 parts substantially as disclosed herein.

Figure 1 represents a view partly in elevation and partly in longitudinal section of an oil burner constructed in accordance with and embodying my invention.

Fig. 2 represents a top plan view of the burner, and

Fig. 3 represents a detail view of the perforated division plate, which acts as a means for evenly directing and distributing the 40 flame jets to the burner.

The burner may be of any shape desired and of the proper size to fit the fire chamber of a stove, and consists of the lower portion A, formed in one end with an opening 45 B, and in its forward lower wall with an opening C, to receive the air supply nozzle or funnel D, said lower portion being also formed with a ledge E, upon which is supported the plate F, provided with openings 50 G, the purpose of which will appear, and upon said lower portion or member A, rests and is secured by means of the lugs H and fastening screws J, the upper burner member K, formed with the flame outlets K', 55 and further formed with a longitudinal de-

pression K², in which is seated the longitudinal oil supply pipe L.

This pipe L fits into the upper member of the burner and is connected by means of the threaded neck L', with a suitable oil 60 supply under pressure, the pipe extending outwardly beyond the burner proper, and having a cap M, secured in its extended end, a sleeve M', being fitted in the cap and forming a bearing for the controlling rod 65 N, having upon its upper end a handle N', and upon its lower end a crank N², said rod being vertically disposed and having the crank thereof connected to the outer exposed end O, of the horizontally disposed 70 needle valve O'.

The oil supply pipe is provided near its outer exposed end with a threaded opening P, in which is fitted the upper threaded end Q, of the cross shaped pipe Q', said upper 75 threaded end extending upward into the supply pipe to receive the gas and prevent sediment or foreign matter from the oil entering said pipe.

As before stated the pipe Q' is in the 80 form of a cross providing the vertical branch Q², and the communicating horizontal branch Q³, one arm of which is formed with a guiding wall R, and cap R', in which bears the outer end of the needle 85 valve O', the other end being pointed at O², and being guided in the wall Q⁴ of the horizontal branch, and for the purpose of cleaning said cross-shaped pipe a cap S is provided which permits the discharge of any 90 sediment from said pipe.

In the opening B in the lower member of the burner, is fitted what I term the mixing chamber T, having an opening therethrough to receive the inner branch of the horizontal 95 pipe, a valve seat U, for the needle valve being provided and the outer portion of the mixing chamber being covered by a screen V, in contiguous relation to which is arranged the ribbon screen V'.

The valve seat U, is disposed adjacent to the air inlet opening of the burner and also near the horizontal funnel W, which acts as a flame collector and in connection with the mixing chamber and air inlet causes a 105 complete mixing of the air with the fuel oil to properly distribute the flame in the lower member and to direct it through the division plate to the outlets in the burner in long jets, thus securing the highest degree of efficiency, 110

the mixing chamber is also provided with an opening W , which admits an additional amount of flame to highly heat the mixing chamber.

- 5 From the foregoing description taken in connection with the drawing the operation of my oil burner will be readily understood and it will be apparent that the oil under pressure and heat forms a gas which passes
 10 from the oil supply pipe to the vertical branch of the cross-shaped feed and distributing pipe, through the mixing chamber and in the lower chamber is mixed with air and the thoroughly mixed oil and air pro-
 15 duces a flame which is directed by the division plate through the openings thereof vertically in long jets through all of the outlets of the burner, thus obtaining the full degree of efficiency from the oil, insuring
 20 economy in the use of the oil and preventing the accumulation of carbon, the needle valve being easily regulated to control the supply of oil to the lower portion of the burner.

I claim:

- 25 1. An oil burner, consisting of the upper member having the flame outlets, the lower member connected to said upper member and having the lower air inlet, the mixing chamber mounted in the outer end of the
 30 lower member, the cross shaped distributing pipe having one horizontal branch entering said mixing chamber, the oil supply pipe connected to the upper vertical branch of said cross shaped distributing pipe, a needle
 35 valve mounted in the horizontal branch of said cross shaped pipe, and a hand operated rod connected to said needle valve.
2. An oil burner, consisting of the upper member having the flame outlets, the lower
 40 member connected to said upper member

and having the lower air inlet, the perforated division plate between the upper and lower members, the mixing chamber mounted in the outer end of the lower member, the cross shaped distributing pipe having one 45 horizontal branch entering said mixing chamber, the oil supply pipe connected to the upper vertical branch of said cross shaped distributing pipe, a needle valve mounted in the horizontal branch of said 50 cross shaped pipe, and a hand operated rod connected to said needle valve.

3. An oil burner, consisting of the upper member having the flame outlets, the lower member connected to said upper member 55 and having a lower air inlet, the perforated division plate between the upper and lower members, the mixing chamber mounted in the outer end of the lower member, the flame collector disposed adjacent to the mixing chamber and the air inlet of the lower member, the cross-shaped distributing pipe having one horizontal burner entering said mixing chamber, the oil-supply pipe connected to the upper vertical branch of the said 60 cross-shaped distributing pipe, the needle valve mounted in and guided by the horizontal branches of said cross-shaped pipe, a valve seat in the inner horizontal branch of said pipe, and a hand-operated rod depending from the oil supply pipe and connected to the outer end of said needle valve for 65 operating the valve.

In testimony whereof I affix my signature in the presence of two witnesses.

WILLIAM D. HAYNES.
